(57) **CLAIM**

The ornamental design for a grater for food products, as shown and described.

DESCRIPTION

FIG. 1 is a partial front view of a grater showing the new design. The Eiffel Tower is shown in dotted lines for illustrative purposes only to indicate the overall shape of a grater and forms no part of the claimed design.

FIG. 2 is a perspective view thereof.

FIG. 3 is a top plan view thereof.

FIG. 4 is a front elevation view thereof; the right side being a mirror image.

FIG. 5 is a left side elevation view thereof; the rear side being a mirror image; and,

FIG. 6 is a bottom elevation thereof.
